SAFETY LAMP

Baudilio Jesus Piqué y Giroud, Marianao
Township, Cuba

Application October 24, 1938, Serial No. 236,674

2 Claims. (Cl. 240—41.3)

My invention relates to safety lamp for use in connection with automobiles, airdromes, and other objects.

The object of my invention is to provide a headlight adapted to emit a compound beam of light comprising a true beam of horizontal rays and a fan of downward deflected rays at different angles.

Another object is to afford means to cut off the horizontally projected beam of light without impairing those rays projected downwardly.

Another object is to provide means to avoid the projection of those rays extending upward from the horizontal.

Another object is to afford means for lessening the intensity of the projected light when the horizontally cast beam is cut off.

I attain these objects by the combination and arrangement of parts illustrated in the accompanying drawings, in which:

Fig. 1 is a longitudinal vertical section of a lamp body, showing the combination of the upper half of a paraboloidal reflector provided with a source of light at its focus, a rotatable hemispherical shell adapted to take the position indicated by broken lines, a lattice of plane plates parallel to the base of the lamp body, and the upper half of a plano-cylindrical lens.

Fig. 2 is a cross-section on the line 2—2 in Fig. 1, showing the device for cutting off, from the light cast by the lamp, the beam of rays horizontally projected.

Fig. 3 is a front view of the lamp.

Fig. 4 is a cross-section on the line 4—4 in Fig. 1.

Fig. 5 is a horizontal cross section on line 5—5 in Fig. 1.

Similar numerals refer to similar parts throughout the several figures.

Referring to the drawings, numeral 1 is used to designate a lamp body, made of metal or any other suitable strong material, whose inner surface from the vertex *a* to point *b* has the shape of the upper half of a paraboloid, and from point *b* to point *c* it makes another kind of curve surface.

The rear end of the lamp body 1 abuts on an annexed box 2 which comprises an upper horizontal plate 3 provided with a hemispherical depression 4 whose center 6 coincides with the focus of the lamp body half paraboloid. Said depression 4 houses a socket 5 adapted to receive a light bulb whose filament will coincide with the point 6, as shown in Figs. 1, 2 and 5. The lateral edges 55 of the plate 3 are prolonged downwardly to form

the walls 23, to which is secured a lid 22 that closes the bottom of box 2.

The inner edge of the lower borders of the lamp body 1 is provided with a rabbet 8, Fig. 4, adapted to receive the lateral borders of the base 7 which is held therein by screws or clamps and whose rear end rests on the plate 3, so that its edge 9 serves as a screen to impede the direct rays from the light bulb at 6 to be projected out, Figs. 1 and 2.

A number of horizontal plates 10, pierced by vertical rods 11, fastened on the base 7 and other rods 12 that join the contour of the group of said horizontal plates 10, make a compact frame proper, on account of its shape, to fit well within the paraboloid of the lamp body 1. Those horizontal plates 10, constitute a fixed lattice adapted to intercept the rays of light projected by the reflector at an angle upward from the horizontal greater than the inclination of a straight line 20 passing between two consecutive plates touching the inner edge of the lower one and the outer edge of the upper one. Therefore, the spacing of said horizontal plates must be regulated in relation to their lengths.

The inner border of the front of the lamp body 1, is provided with a slot 13 which becomes wider downwards in both sides and it is adapted to receive and house the edge of the upper half of a plano-cylindrical lens 14 whose base—which is rectangular—will rest in a rabbet 15, cut in the edge of the front of the base 7. The plane face of the lens 14 is placed inwardly and at right angle to the plates 10, Fig. 1.

A hemispherical shell 16, concentric with the hemispherical depression 4, has a slot whereby a socket 5, passes and said shell 16, is provided with two axles 17 and 17a whose ends are adapted to turn in proper bearings made in the lamp body 1, Figs. 2 and 3.

An arm 18 attached to the axle 17, passes through a slot cut in the plate 3 and it has its lower end connected to a flexible rod 19 which comes from the exterior through a suitable housing, so that when said flexible rod 19 is pulled 45 it pulls the end of the arm 18 causing the axle 17 to turn with the shell 16 into the position shown by broken lines in Fig. 1. And vice versa, when the flexible rod 19 is pushed, it pushes the end of the arm 18 causing the axle 17 to turn back with 50 the shell 16 into the position shown by heavy lines in Fig. 1.

An arm 20 attached to the axle 17a passes through a slot made in the plate 3 and carries on its end a contact adapted to operate a rheo- 55

stat 21 which regulates the electric current and therefore the intensity of the light emitted by the bulb at 6.

The inner surfaces of the lamp body 1, and the 5 inner surface of the shell 16 as well as the lower faces of the plates 10 are polished, in order to reflect the light while the surfaces of the upper faces of the plates 10, the plate 3 and the base 7 are porous, dull and without any luster so that 10 they may not reflect any light.

The front elevation of the lens 14 is semicircular, as shown in Fig. 3, while any vertical section of the same at right angle to its plane face will be the upper half of a circular segment, 15 because, as shown in Fig. 1, said lens 14 is the upper half of a plano-cylindrical lens having its generator line horizontal and parallel to its plane face.

With this disposition of the lens 14, when a 20 beam of horizontal rays of light falls normally on its plane face, those rays, passing through the lower third of the lens, do not suffer any appreciable refraction, because they meet normally the front face of the lens, as it is shown 25 by a broken line in Fig. 1; while else rays passing through the lens higher than its lower third will meet its front cylindrical face leaning backwardly and as they are passing into the air, which is optically a rarer medium than the lens, 30 they will be refracted from the normal to the curved surface. Then the deflection will be downwardly, and greater as the rays pass higher through the lens 14. In this way the rays cast by the uppermost portion of said lens are those 35 which illuminate the roadway immediately in front of the vehicle.

Now, when the flexible rod 19 is pulled and it pulls the end of the arm 18, as herein before described; the shell 16 turns into the position shown by broken lines in Fig. 1 and intercepts 40 the rays of light that go from the bulb at 6, to the portion of the vertex *a* of the half paraboloidal reflector 1 and thereabout, so all the reflected rays which would pass through the 45 lower third of the lens 14 are cut off, and there-

fore, the suppressible far reaching horizontal beam of rays of the compound beam of light cast by the lamp is also cut off. Meantime, the arm 20 will have turned carrying its contact against the rheostat 21 diminishing the intensity of the 5 remaining light projected by the lamp to the standard allowed for city use.

I claim:

1. In a safety lamp, the combination of the upper half of a paraboloidal reflector provided 10 with a source of light at its focus; a rotatable hemispherical shell whose center coincides with the focus of the above named paraboloidal reflector; means to rotate said hemispherical shell into a position proper to impede the light from 15 the focus to fall on a portion of the reflector comprising from its vertex to the parameter or thereabout; a number of long horizontal parallel plates spaced in relation to their lengths; and the upper half of a plano-cylindrical lens placed 20 with its plane face toward the reflector and at right angle to the above named horizontal plates.

2. In a safety lamp, the combination of an upper half of a paraboloidal reflector provided with a source of light at its focus; a number of 25 long horizontal parallel plates spaced in relation to their lengths; an upper half of a plano-cylindrical lens; a hemispherical shell, adapted to fulfil two functions, one as a screen, and the other as a reflector whose center coincides 30 with the above-named focus of the paraboloidal reflector and the source of light; means to rotate said hemispherical shell into two positions, one interposed between the source of light and a portion of the paraboloidal reflector comprised 35 from its vertex to the parameter or thereabout, and the other position at the side of the source of light opposite to the paraboloidal reflector; and a rheostat which regulates the electric current and therefore the intensity of the light 40 emitted by the source of light, acted by the same means which causes the hemispherical shell to rotate.

BAUDILIO JESUS PIQUÉ Y GIROUD.
